UNITED STATES PATENT OFFICE.

RALPH M. SHARAF, OF NEW YORK, N. Y., ASSIGNOR TO R. M. SHARAF MACHINE CO.,
OF BOSTON, MASSACHUSETTS, A CORPORATION OF MASSACHUSETTS.

LOOP-TAKER MECHANISM FOR ZIGZAG SEWING MACHINES.

Application filed November 24, 1917, Serial No. 203,658. Renewed December 2, 1919. Serial No. 342,015.

To all whom it may concern:

Be it known that I, RALPH M. SHARAF, a citizen of the United States, and resident of the borough and county of the Bronx, city 5 and State of New York, have invented certain new and useful Improvements in Loop-Taker Mechanisms for Zigzag Sewing Machines, of which the following is a specification.

10 My invention relates to that type of zigzag sewing machines in which a laterally moving needle cooperates with a loop-taker or hook having a bodily shifting motion, in addition to turning about its own axis. Here- 15 tofore, in machines of this character, the shifting movements of the loop-taker have been in the nature of an oscillating or reciprocatory motion given to the loop-taker axis, or to the carrier in which the loop- 20 taker is journaled. My present invention provides means for obtaining the shifting movements of the loop-taker by causing its axis to travel in a circular or rather cylindrical path, thus simplifying the mecha- 25 nism and enabling it to be readily operated at high speed, inasmuch as the travel of said axis is always in the same direction.

A specific and preferred embodiment of this invention will now be described in detail with reference to the accompanying drawings, in which—

Figure 1 is a plan view of a sewing machine embodying my present invention (with parts omitted);

35 Figure 2 is an elevation, partly in section on line 2—2 of Fig. 1, certain parts being omitted;

Figure 3 is a front elevation with parts broken away;

40 Figure 4 is a bottom view of certain parts shown in Fig. 2;

Figures 5 and 6 are sections on lines 5—5 and 6—6 respectively of Fig. 2.

The mechanism for imparting a lateral movement to the needle may be of any approved character, and in the example illustrated I have indicated two needles 10 connected rigidly with a needle bar 11 reciprocating vertically in a frame or gate 12 which oscillates about a vertical axis 13 to give the needles their lateral movement, transversely to the line of feed, or path of the fabric. This needle-jogging mechanism may be operated in any well known or approved manner, for instance as set forth in my applica-

tion for Letters Patent of the United States, filed April 2, 1917, Serial No. 159,058. While I have shown two needles 10, and a separate loop-taker cooperating with each of them, I do not wish to restrict myself to such duplicate construction.

It will be understood that the needle-bar 11 reciprocates above the base plate or table 14, the needles on their downward stroke passing through a suitable throat-plate 15. The needle movement is of the well known type, the needle receiving a lateral movement between each two successive downward or stitching strokes, such lateral movements being alternately in opposite directions.

On the downward stroke, the needle comes into operative relation to a loop-taker 16 provided with a hook 16' or 16'' respectively to perform the usual function in connection with the loop of the needle-thread. This loop-taker is shown as made with a two-piece vertical trunnion 17, 17' of circular cross section extending downwardly at the center of the loop-taker. The two sections 17, 17' are normally held together by a screw 18 accessible from above to connect or disconnect said sections, and preferably the upper section 17 of the trunnion or pin is integral with the loop-taker, and the lower section 17' is held to turn with the upper section, so that normally the pin 17, 17' is rigid with the loop-taker 16 so as to turn therewith, but this is not essential. The trunnion or pin 17, 17' fits into a corresponding vertical bore of a shaft 19, said bore being eccentric relatively to the shaft axis, and thus the loop-taker 16 is connected pivotally at its center to the shaft 19 at a distance from the axis of such shaft. The lower end of the bore in the shaft is shown enlarged, as at 19', to provide a shoulder forming a stop for a flange 17'' at the lower end of the center pin 17, 17', and thus preventing upward withdrawal of said pin while its sections are connected. The shaft 19 is journaled in a vertical sleeve 20 mounted to rotate in a normally stationary bearing 21, it being understood that the outer surface of said sleeve is co-axial with its inner surface, so that rotation of the sleeve 20 will not affect the shaft 19 journaled therein. At its upper end the sleeve 20 carries a pin 20' extending into a radial groove 16' of the loop-taker, thus forming a driving connection between the sleeve and the loop-

taker. Thus while the sleeve 20 rotates, the loop-taker 16 will rotate also, but about an axis eccentric to that of said sleeve. Rotation may be imparted to the sleeve 20 by 5 making it integral or rigid with a bevel wheel 22, in mesh with a bevel wheel 23 held to turn with a shaft 24 rotated continuously, by gearing 25 from a shaft 26 which is in turn operatively connected to the main driving shaft of the machine so as to be driven thereby.

The loop-taker is rotated continuously about its own axis as just explained, and said axis itself is shifted or caused to travel 15 in a circular or rather cylindrical path. This is accomplished by rotating the shaft 19. In the particular construction illustrated, this rotation is intermittent, but I do not wish to be understood as restricting myself to such 20 specific embodiment. To secure this intermittent rotation, a mutilated gear having two toothed segments 27 of almost 180° each is made rigid or integral with the shaft 19, at the lower end thereof, the toothed segments 25 being separated by short blocks or holding portions 27' having concave lower surfaces concentric with the shaft 24 when said holding portions are in engagement with the smooth circumferential portion 28 30 of a mutilated gear rigidly connected with the adjacent bevel gear 23. This portion 28 is about 180° in extent, and is separated from the toothed portion 28', of substantially like extent, by notches 28'' to insure 35 proper mesh at the beginning of each driving period.

Considering only one of the needles and the loop-taker cooperating therewith, the 40 operation of the mechanism described above will be as follows:

Figures 1 to 3 show the loop-takers in their extreme left-hand positions with the hooks 16' and 16'' in position to cooperate 45 with the needles which have passed through the throat-plate.

The axis of each of the loop-takers is stationary in the position indicated by A. The needles go up, shift laterally to their right hand positions and then go down in the new 50 positions. During the interval between the rise of the needles and their succeeding downward movement the hollow shafts 19 are rotated through half a revolution by their connections with the main driving 55 shaft so that the axis of each of the loop-takers, traveling through the circular or cylindrical arc indicated at a (Fig. 4) reaches the other extreme position A' which is diametrically opposite to A with respect 60 to the axis B about which the shaft 19 and sleeve 20 turn. The loop-takers are thus positioned for proper coaction with the needles in their right hand positions. The needles then rise again above the throat-plate and 65 are shifted laterally toward the left, pre-

paratory to their downward movements in their left hand positions. Prior to such movement, however, each of the hollow shafts 19 is again rotated through half a revolution by its connections with the main driving shaft so that the loop-taker axis, traveling through the other circular or cylindrical arc a' (of 180°) is brought back to the original position A, whereupon the cycle of operations is repeated. It will be understood that in this particular construction, the bevel wheels 22, 23 are of the same diameter, and the toothed segments 27, 28' have equal radii, yet owing to their special construction, each revolution of the gear 28, 28' will produce only a half revolution of the shaft 19. 75

When two needles and two loop-takers are employed, as illustrated, the arrangement is practically a duplication of the one described above, except that the position of one hook 16' relatively to the plane containing the loop-taker axis and the axis of the sleeve 20, is substantially the reverse of the position of the other hook 16'', the two hooks being in 80 positions about 180° apart, relatively to their axes, at the time they cooperate with the respective needles, as indicated in Figure 1.

In certain cases, it may be desirable to provide for an adjustment of the distance between the loop-takers, to cooperate with 85 needles of different spacing, as when the needle holder is removable and exchangeable. For thus adjusting the loop-takers, I have shown a mechanism of the type disclosed in my application for Letters Patent of the 90 United States filed April 2, 1917, Serial No. 159,060. The normally stationary bearings 21 are slideable toward and from each other along guideways 29' of the frame or bed-plate 29, and to each of the bearings 105 is secured rigidly a yoke 30 engaging a groove 31' of a sleeve 31 to which the adjacent gears 23 and 28, 28', are secured rigidly. Each sleeve 31 is slideable lengthwise of the shaft 24, yet held to rotate therewith, as by 110 means of a key and groove. Stationary bolts 32, secured to the frame 29, extend at right angles to the path of the slideable bearings 21, through slots 21' parallel to said path. The upper surface of each bearing engages 115 the lower surface of the frame, and the bearings are normally held stationary by the upward pressure of sleeves 33, fitted to slide on said bolts below the bearings, and normally urged upward by a pressure plate 34 120 having holes 34' for the passage of the bolts. The pressure plate 34 slides on said bolts, and its central portion is engaged by the upper end of a clamping or locking screw 35, threaded into a central opening of a plate 36, 125 likewise provided with holes (36') to receive the bolts 32. The lower ends of the bolts are screw-threaded to receive nuts 37, the function of which is to form an abutment or backing for the plate 36 when a clamping 130

pressure is applied by tightening the screw 35, and also to prevent the plate 36 and the parts above it from dropping off when the screw 35 is loosened. The nuts 37 are so placed as to allow a certain looseness for the movement of the plate 34 and sleeves 33 lengthwise of the bolts 32, and in the normal clamping position the upper surface of the plate 36 is out of engagement with the lower 10 surface of the pressure plate 34.

When the screw 35 is loosened to release the bearings 21, the latter may be adjusted along the guideways 29'. For the purpose of effecting an equal adjustment of the two 15 bearings simultaneously, I have shown a screw 38 threaded oppositely from the center and screwing through lugs 21" provided on the respective bearings 21. Longitudinal movement of this screw is prevented by 20 aligning screws 39 which form bearings supporting the screw 38 and are normally stationary, but may be adjusted lengthwise by turning them in their stationary supporting brackets 29". On the central portion of the 25 screw 38 is secured rigidly a spiral gear 38' in mesh with a similar gear 40' on a shaft 40 journaled in a stationary bearing 29" and provided with a knurled head 40" at its outer end. By turning this head (at a time 30 when the bearings 21 are free to slide), the shaft 40 and the screw 38 will be rotated, the ends of the screws 39 forming stationary bearings for the ends of the screw 38. This will cause the two bearings 21 to move 35 toward or from each other according to the direction of the rotation, but the positions of the two bearings will always remain symmetrical to a stationary central plane. After adjusting the bearings to the desired distance, the screw 35 is tightened to lock them 40 in position.

It will be observed that the diameter *b* of the circular path described by the loop-taker axis is approximately equal to the lateral 45 movement *c* of the needle.

The particular loop-taker illustrated is adapted to contain a bobbin-case and bobbin (not shown) for a lower thread to produce a lock-stitch in the well-known manner. 50 However, this is not essential, as a machine having loop-takers with my novel type of motion may be operated without any thread other than the needle thread, in which case a chain-stitch is produced.

While I have shown and described a preferred and satisfactory embodiment of my invention, it is obvious that changes may be made therein within the spirit and scope thereof, as defined in the appended 60 claims.

I claim:

1. In a sewing machine, a rotary loop-taker, a member mounted to turn about a stationary axis parallel to the axis about 65 which the loop-taker rotates, said loop-taker

being journaled in said member, means for rotating the loop-taker about its own axis, and means for turning said member to cause the loop-taker axis to travel through a closed circular path around said stationary axis. 70

2. In a sewing machine, a sleeve mounted to turn about a stationary axis, a shaft journaled in said sleeve coaxially and provided with an eccentric socket, a loop-taker provided with a central pin seated in said socket, cooperating means on said sleeve and loop-taker to drive the loop-taker from said sleeve, and means for turning said shaft to alter the position of the eccentric socket and 75 of the loop-taker axis. 80

3. In a sewing machine, a bearing, a sleeve journaled therein, a shaft journaled in said sleeve co-axially, a loop-taker, the central portion of said loop-taker and an eccentric portion of said shaft having mating formations to keep the loop-taker axis in a position eccentric to the shaft axis, cooperating means on said sleeve and loop-taker to drive the loop-taker from said sleeve, and means for turning said shaft to alter the position of the eccentric socket and of the loop-taker axis. 85 90

4. In a sewing machine, a shaft mounted to turn about a stationary axis, a loop-taker mounted to turn about an axis eccentric to that of said shaft, a driving connection between said shaft and said loop-taker, and means for shifting the loop-taker axis in a closed circular path the center of which is 95 on said stationary axis. 100

5. In a sewing machine, a shaft mounted to turn about a stationary axis, a loop-taker mounted to turn about an axis eccentric to that of said shaft, a driving connection between said shaft and said loop-taker, and means for shifting the loop-taker axis in a closed curvilinear path. 105

6. In a sewing machine, a shaft mounted to turn about a stationary axis, a loop-taker mounted to turn about an axis eccentric to that of said shaft, a driving connection between said shaft and said loop-taker, and means for shifting the loop-taker axis in a closed curvilinear path surrounding said 110 stationary axis. 115

7. In a sewing machine, a bearing, a sleeve journaled therein, a shaft journaled in said sleeve co-axially, a loop-taker, the central portion of said loop-taker and an eccentric portion of said shaft having mating formations to keep the loop-taker axis in a position eccentric to the shaft axis, mating parts on said loop-taker and sleeve, in sliding engagement with each other toward and from the center of the loop-taker, and forming a driving connection between said sleeve and loop-taker, and means for operating said sleeve and said shaft. 120 125

8. In a sewing machine, a bearing, a sleeve 130

journaled therein a shaft journaled in said sleeve co-axially, a loop-taker, the central portion of said loop-taker and an eccentric portion of said shaft having mating formations to keep the loop-taker axis in a position eccentric to the shaft axis, mating parts on said loop-taker and sleeve, in sliding engagement with each other toward and from the center of the loop-taker, and forming 5 a driving connection between said sleeve and loop-taker, a driving gear wheel for operating said sleeve, and another driving gear wheel rotating in unison with the first-named gear wheel, for giving said shaft a smaller 10 number of revolutions than said sleeve.

9. In a sewing machine, a bearing, a sleeve journaled therein, a shaft journaled in said sleeve co-axially, a loop-taker, the central portion of said loop-taker and an eccentric 20 portion of said shaft having mating formations to keep the loop-taker axis in a position eccentric to the shaft axis, mating parts on said loop-taker and sleeve, in sliding engagement with each other toward and from 25 the center of the loop-taker, and forming a driving connection between said sleeve and loop-taker, a driving gear wheel for rotating said sleeve continuously, and a mutilated driving gear wheel, rotating in 30 unison with the first-named gear wheel, for giving said shaft intermittent partial rotations, of a half-revolution each.

10. In a sewing machine, a needle having lateral movements, a rotary loop-taker arranged 35 to cooperate with said needle, and means for causing the axis about which the loop-taker rotates, to travel in a circular path the diameter of which is approximately equal to the lateral movement of the needle.

11. In a sewing machine, a needle having lateral movements, a loop-taker mounted to turn and arranged to cooperate with said needle, and means for causing the axis about 40 which the loop-taker turns, to travel in a

closed path the lateral diameter of which is 45 approximately equal to the lateral movement of the needle.

12. In a sewing machine, a needle reciprocating lengthwise and also moving transversely of the line of feed, and a loop-taker 50 mounted to turn about an axis parallel to the needle and arranged to cooperate with said needle, and means for causing the axis about which the loop-taker turns, to travel in a closed curvilinear path the lateral diameter 55 of which is approximately equal to the transverse movement of the needle.

13. In a sewing machine, a shaft mounted to turn about a stationary axis, a loop-taker connected to the shaft and mounted to turn 60 about an axis eccentric to that of said shaft, and means for shifting the loop-taker axis in a continuous curvilinear path.

14. In a sewing machine, a shaft mounted to turn about a stationary axis, a loop-taker 65 connected to the shaft and mounted to turn about an axis eccentric to that of said shaft, and means for shifting the loop-taker axis in a closed continuous curvilinear path.

15. In a sewing machine, a hollow shaft 70 mounted to turn about a stationary axis, a loop-taker operatively connected to the shaft, a shaft carrying the loop-taker and mounted within the hollow shaft eccentrically of said shaft, and means for shifting the shaft carrying the loop-taker. 75

16. In a sewing machine, a hollow shaft mounted to turn about a stationary axis, a loop-taker connected to the shaft and mounted to turn about an axis eccentric to 80 that of the shaft means enclosed within said shaft for supporting the loop-taker, and means for intermittently shifting the loop-taker axis.

In testimony that I claim the foregoing 85 as my invention, I have signed my name.

RALPH M. SHARAF.
